CLAIM

I claim the ornamental design for a flush valve, as shown and described.

DESCRIPTION

FIG. 1 is a perspective view of a flush valve showing my new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.
